UNITED STATES PATENT OFFICE

HENRY JOSEPH ROUND, OF LONDON, AND NOEL MEYER RUST, OF CHELMSFORD, ENGLAND, ASSIGNORS TO RADIO CORPORATION OF AMERICA, A CORPORATION OF DELAWARE

RADIORECEIVER

Application filed April 6, 1925, Serial No. 20,902, and in Great Britain April 9, 1924.

This invention relates to means for obtaining negative resistance effects, and to improvements in radio receivers.

In applying the invention to diminishing the resistance of an aerial (in other words, to obtain negative resistance), we connect or couple to the aerial inductance a circuit containing a crystal and a condenser in series with one another, the crystal being shunted 5 with a high resistance and a battery in series with one another. To the aerial inductance we also connect or couple a circuit containing a rectifier (preferably another crystal) in series with a telephone or pair of telephones 10 which is shunted by a condenser and with a 15 potentiometer.

In order to give some idea of the constants of these circuits we may say that we have found the following to be suitable for use in 20 the reception of broadcasted news with an aerial consisting of an ordinary single wire of length about 80 feet and height about 20 feet, connected through a .003 mfd. condenser and an ordinary broadcast variometer to 25 earth. To the high potential end of the variometer was connected one side of a variable condenser having a maximum value of about .0008 mfd.; during working the value of this condenser was between .0001 and .00025. The 30 other side of this condenser was connected to a crystal the cat's whisker contact of which was connected to the earthed end of the variometer. The crystal was also connected to one end of a resistance which could be varied 35 between 1000 and 12000 ohms, and the other end of this resistance was connected to the positive pole of a 50 volt battery which could be tapped with variations of 1½ volts, the negative pole being connected to the cat's 40 whisker. The best results were obtained with the highest values of the resistance and of the battery voltage practicable, but not more than 50 volts are advisable as with higher voltages the cat's whisker is apt to get burnt 45 when adjusting. To the high potential end of the variometer was also connected a carbondum crystal, and its metallic contact was connected to a pair of ordinary high resistance telephones shunted by a 10 jar disc 50 condenser generally used at a low value, and

this again to the usual potentiometer and then to the lower end of the variometer.

When receiving wave lengths of the order of 350 meters the aerial inductance may be of the order of 150 microhenries. For 3500 meters the value of the aerial condenser would depend on the aerial employed while for small aerials such a condenser would not be necessary except for fine tuning. The value of the condenser in series with the negative resistance crystal would be of the order of .002 mfd. and that of the aerial inductance from 1000 to 1500 microhenries, while for greater wave lengths the values of this condenser and of the inductance should be roughly proportional to the wave length. 55

We have found that to obtain the negative resistance effect, the best results are obtained with crystals of low resistance, thus arzenite, silicon, zincite, tellurium, magnetite and iron pyrites, may be employed, these names being arranged in the order of the efficiency of the crystals. 70

Arzenite is the trade name of a new product and is a nearly pure crystalline form of zinc oxide. 75

The characteristic curve of each of these crystals possesses a sharply defined kink or knee and to obtain the negative resistance effect the value of the resistance in series with the crystal should be so great that the part above the knee of the characteristic of the crystal and resistance combined is not too steep, otherwise the circuit will be unstable. 80

We have found, however, that by using a smaller resistance so that the combination of the crystal and resistance has a negative characteristic, oscillations will be set up in the crystal circuit and then super-regenerative effects can be obtained, owing to the automatic quenching effects of the rectifier crystal. 85

We have found also that the negative resistance effect to be obtained from crystals of arzenite, zincite, tellurium and magnetite (especially the first two) is increased if the operative surface of the crystal is fused. The method of fusing is, preferably, to secure the crystal in a cup with zinc, care being taken to push the crystal well into the molten zinc. 95 100

before it sets, so as to ensure that the crystal is well gripped by the metal as it cools. The crystal is then gripped in a vise which is connected through a 7.5 ohm resistance to the positive pole of a 100 volt source of direct current. A carbon electrode is connected to the negative pole and an arc is struck between the carbon and the face of the crystal. The carbon is moved backwards and forwards several times so that the arc is drawn out and contracted. A slight crater of darkly glazed material is thus formed on the crystal. The carbons for this process should be fairly small and kept sharply pointed.

15 We may employ more than one crystal or crystal contact and preferably we employ a separate control resistance for each crystal.

We can thus afford to damp our aerial more by lower resistance rectifiers or by rectifiers 20 in parallel, providing we have more negative resistance furnished by the crystals in parallel referred to above, to provide the necessary energy for obtaining the same potential across the rectifiers. In cases where 25 better tuning is required, we find it advantageous to use a coupled circuit to our crystal and to apply a negative resistance crystal in a similar way to the secondary circuit or to both aerial and secondary circuit. It is well 30 known that maximum transfer of energy at resonance will then take place at a much looser coupling and the result of two low damped circuits coupled loosely will be very sharp over all resonance.

35 We may also employ a crystal connected in such a circuit for reducing the damping of a rejector circuit employed for eliminating one particular wave length.

In place of employing the crystals referred 40 to above, we may employ a metal plate which has had a film of oxide produced on it by striking an arc on its surface. Suitable metals for use in this way are zinc, aluminium, iron, copper and nickel.

45 We apply to the film of oxide on such a plate a loose contact, such as a cat's whisker, and connect this contact to a resistance and a source of current and so to the back of the plate. The contact and the back of the plate 50 we also connect to an output circuit and are thus enabled to obtain in this output circuit a negative resistance effect or oscillations as desired.

In some cases we may even employ a plate 55 on which a film of oxide has been produced naturally in the atmosphere or by other means, but such plates are not nearly so efficient as those in which the oxide has been produced by an arc. In fact we have not yet 60 been able to produce stable oscillations from such plates, though we have obtained negative resistance effects from them, whereas with plates oxidized by an arc we have obtained oscillations of wave lengths of 8000 65 meters and over. We have found, however,

that by subjecting a zinc plate which has been coated with white oxide by an arc to a subsequent treatment with the arc a reddish brown oxide can be formed upon the white oxide and that oscillations as short as 600 70 meters can be obtained from points near the junction of this reddish brown oxide with the white oxide.

Preferably we so manipulate the arc that this brown oxide is formed in a ring upon 75 the white oxide.

The accompanying drawing illustrates various circuits in accordance with this invention. In the drawing Figure 1 illustrates diagrammatically an approved form of our invention and Figures 2, 3 and 4 illustrate modifications thereon.

In Fig. 1, the circuit A comprises a condenser 2, crystal or plate 3, as above described, a loose contact 4, such as a cat's whisker which is applied to the crystal on plate 3, high resistance 5, and current source 6 connected to the aerial inductance 1, while the circuit B comprises rectifier 7 such as a carborundum crystal and telephones 8, also 90 connected to the aerial inductance 1.

In the modification shown in Fig. 2, the circuit A is inductively coupled to the inductance 1, the circuit B being connected to the said inductance.

In Fig. 3 the circuit A is connected to the inductance 1 and the circuit B is inductively coupled thereto. In this case a condenser 9 is provided in circuit B.

Fig. 4 illustrates a further modification, 100 in which three circuits A are employed, two of the said circuits being connected to the inductance 1, and serving to produce negative resistance effects therein. The signals in the aerial are transferred to a secondary circuit and rectified as at B, negative resistance effects being introduced into this secondary circuit by the third circuit A.

Having described our invention, what we 110 claim is:

1. Means for effectively reducing the resistance of an aerial circuit provided with an inductance, said means including an adjustable condenser and a rectifying crystal or oxidized plate in series therewith connected across said inductance, and a source of current and a resistance in series therewith connected in parallel with said rectifying crystal or oxidized plate.

2. Means for effectively reducing the resistance of an aerial circuit provided with an inductance, said means including a circuit comprising an adjustable condenser and a rectifying crystal or oxidized plate in series therewith, and a source of current and a resistance in series therewith connected in parallel with said rectifying crystal or oxidized plate, said last mentioned circuit being inductively coupled to the aerial inductance.

3. Means for reception, consisting of an 130

- 65 aerial inductance, two circuits, one of which is connected to the inductance and contains a rectifying crystal and a condenser in series with one another, and a high resistance and a source of current connected across said crystal, the second circuit also being connected to the inductance and containing a rectifier in series with a sound responsive means. 70
4. Apparatus for receiving high frequency signals, including a detector circuit and an independent auxiliary circuit coupled thereto, said auxiliary circuit including a rectifying crystal means for obtaining a negative resistance effect and a biasing battery electrical- 75 ly associated with the crystal means. 80
- 10 5. Apparatus for receiving high frequency signals, including a detector circuit and an independent auxiliary circuit coupled thereto, said auxiliary circuit including a rectifying oxidized plate shunted by a biasing battery for obtaining a negative resistance effect. 85
- 20 6. Apparatus for receiving high frequency signals, including a detector circuit and an independent auxiliary circuit coupled thereto, said auxiliary circuit including a low resistance rectifying crystal for obtaining a negative resistance effect, the operative face of the crystal being fused and a source of potential connected to said crystal. 90
- 30 7. Apparatus for receiving high frequency signals, including an aerial, a circuit coupled to said aerial and comprising a rectifier and sound detecting means, and an independent auxiliary circuit also coupled to the aerial for effectively reducing the resistance of the aerial, comprising a condenser and a low resistance rectifying crystal, and a source of current and a resistance in series therewith connected across said crystal. 95
- 40 8. In a circuit, means for obtaining negative resistance whereby the circuit resistance may be effectively reduced, said means including a rectifying crystal of low resistance, the current-potential characteristic curve of which possesses a sharply defined knee. 100
- 45 9. Means for obtaining negative resistance, including a rectifying crystal or plate having a film of oxide formed upon its surface. 110
- 50 10. An arrangement for producing negative resistance effects comprising a rectifying crystal or oxidized plate shunted by a biasing battery, said crystal or oxidized plate having the characteristic of decreasing resistance 115 with increase of potential beyond a certain critical value. 120
- 60 11. Means for obtaining negative resistance effects comprising a tuned circuit having in series an inductance, a variable condenser and a low resistance rectifying crystal, and a biasing battery and resistance in parallel with said crystal, the arrangement being such that with increase of potential beyond a certain critical value the resistance of the crystal 125 will decrease. 130
